(57) **CLAIM**

The ornamental design for a sweeper charger, as shown and described.

DESCRIPTION

1. Sweeper charger

1.1 : Front

1.2 : Back

1.3 : Right

1.4 : Top

1.5 : Bottom

1.6 : Perspective

1.7 : Perspective

1.1 is a front elevation view of a sweeper charger of our new design; 1.2 is a back elevation view thereof; 1.3 is a right side elevation view thereof; 1.4 is a top plan view thereof; 1.5 is a bottom plan view thereof; 1.6 is a perspective view thereof; and 1.7 is another perspective view thereof; the product incorporating the design is mainly used for charging a sweeper or the like; and the drawing designated to best show the essential features of the design is 1.6.

1 Claim, 7 Drawing Sheets
